DESIGN FOR A LIGHTING FIXTURE OR SIMILAR ARTICLE

Ignatius Arthur Ganger, New York, N. Y.

Application September 12, 1942, Serial No. 108,220

Term of patent 3½ years

To all whom it may concern:

Be it known that I, Ignatius Arthur Ganger, a citizen of the United States, residing at Manhattan, county of New York, city and State of New York, have invented a new, original, and ornamental Design for a Lighting Fixture or Similar Article, of which the following is a specification, reference being had to the accompanying drawing, forming part thereof, wherein—

Figure 1 is a front elevational view of a lighting fixture or similar article showing my new design, and

I claim:

The ornamental design for a lighting fixture or similar article, substantially as shown.

IGNATIUS ARTHUR GANGER.
